THERMAL REFORMING OF A CATALYTIC REFORMATE

Warren Nevin Norton Knight, Sunbury-on-Thames, England, assignor to The British Petroleum Company Limited, London, England, a British joint-stock corporation

Application November 15, 1956, Serial No. 622,337

Claims priority, application Great Britain November 24, 1955

3 Claims. (Cl. 208—65)

This invention relates to motor fuels for the operation of internal combustion engines.

Hydroforming is a well-known process for producing high octane motor gasolines from low octane petroleum naphthas. In the hydroforming process, the low octane petroleum naphtha is contacted at elevated temperature in the presence of hydrogen with a catalyst capable of converting naphthenes into aromatics to give a product of greatly increased octane number. A hydroforming process that has been widely adopted uses a platinum-containing catalyst and such a process will hereinafter be referred to as Platforming. The catalytic reformate of such a process will hereinafter be referred to as Platformate. It has long been known that the octane number of a catalytic reformate can be increased by thermal reforming, and it has recently been proposed to apply this principle to the product of the Platforming process.

It has now been discovered that there are advantages in subjecting portions of the total catalytic reformate to thermal reforming separately.

According to the invention, a catalytic reformate is separated into a high boiling fraction and a low boiling fraction, the two fractions are subjected to thermal reforming separately, the low boiling fraction being reformed at a greater severity than the high boiling fraction, and the products of the thermal reforming operations are blended to produce a high octane gasoline.

The cut point between the low boiling and high boiling fractions of the catalytic reformate should preferably lie within the range 110° to 150° C.

The thermal reforming operations are preferably carried out at temperatures within the range 1,000 to 1,200° F. and at a pressure within the range 200 to 1,200 p.s.i.g., and the conditions in the two operations are preferably such that conversion to C₃ and lighter on the low boiling fraction is in the range 20% to 35% wt. and on the high boiling fraction 5% to 20% wt.

The process according to the invention has the advantage that it is possible to subject the low boiling fraction to the severe reforming conditions necessary to produce the maximum upgrading, whereas these conditions cannot be applied to the total catalytic reformate without causing excessive coking, while low severity reforming conditions are sufficient to upgrade the high boiling fraction. As a result, it is possible to produce a final gasoline having an octane number above that of the gasoline produced by thermally reforming the total catalytic reformate.

The process of the invention is particularly applicable to the product of the Platforming process, and an example of its application thereto will now be described:

A straight-run Kuwait naphtha (90°-190° C. boiling range) was hydroformed over a catalyst having the following composition:

	Percent wt.
Platinum	0.37
Fluorine	0.51
Chlorine	0.26
Alumina	98.8

2

under the following conditions:

Pressure	500 p.s.i.g.
Catalyst inlet temperature	920° F.
Gas recycle rate	9200 s.c.f./b.
Space velocity	2.0 v./v./hr.

A Platformate of 82 octane number (Research) was obtained and was distilled in a 10 plate continuous column to give a light Platformate of 130° C. ASTM end point (60% wt.) and the corresponding residue (40% wt.).

The light Platformate (75 octane number) was reformed at 750 p.s.i.g. and at 1,060° F. to give the following product distribution:

	Percent wt.
C ₃ and lighter	26
C ₄	17
Gasoline	50
Polymer	7

The gasoline (30% wt. on total Platformate) had an octane number of 97 research. The heavy Platformate (94 octane number) was reformed at 750 p.s.i.g. and 1,030° F. to give the following product distribution:

	Percent wt.
C ₃ and lighter	7
C ₄	3
Gasoline	87.8
Polymer	2.2

The gasoline (35% wt. on total Platformate) had an octane number of iso-octane+0.8 ml. TEL/USG octane number (Research).

The blending of these two thermally reformed gasolines gave a yield of 65% wt. on total Platformate of a gasoline of iso-octane+0.30 ml. TEL/USG octane number (Research). If the total Platformate were reformed, the maximum octane number obtainable without excessive coking of the unit would be iso-octane+0.05 ml. TEL/USG.

The invention is illustrated diagrammatically in the accompanying flow-sheet.

Naphtha is fed through line 1 to a catalytic reformer 2 and reformed debutanized gasoline passes via line 3 to the middle of a distillation column 4, which separates the gasoline into two fractions with a cut point in the region of 110-150° C. The light gasoline taken off overhead through line 5 has a relatively low octane number and is thermally reformed in reformer 6 at a relatively high severity. The heavy gasoline withdrawn from the column 4 through line 7 is thermally reformed in reformer 8 at a lower severity, since it has initially a relatively high octane number. The products from both thermal reformers are re-run and debutanized and pass via lines 9 and 10 respectively to a common line 11 for blending and storage.

I claim:

1. A process for producing gasoline of increased octane number from a liquid catalytic reformate, which reformate is a product of a hydroforming process in which is used a platinum-containing catalyst, comprising separating the catalytic reformate into a high boiling liquid fraction and a low boiling liquid fraction, thermally reforming two fractions separately, each at a temperature within the range 1000° to 1200° F. and a pressure within the range 200 to 1200 p.s.i.g., but at different severities, the low boiling fraction being reformed at the greater severity, and blending the products of the thermal reforming operations.

2. A process as claimed in claim 1 wherein the cut point between the low boiling and high boiling fractions of the catalytic reformate lies within the range 110° to 150° C.

3. A process as claimed in claim 1 wherein the low boiling fraction is thermally reformed to give a conversion to C₃ and lighter hydrocarbons in the range 20% to 35% and the high boiling fraction is thermally reformed to give a conversion to C₃ and lighter hydrocarbons in the range 5% to 20%. 10 164,158
